GARMENT CLASP

Robert Finkbeiner, New York, N. Y., assignor to
The American Suspender Company, New York,
N. Y.

Application September 21, 1933, Serial No. 690,392

7 Claims. (Cl. 24—250)

This invention relates to garment clasps, especially adapted for use with garters and suspenders.

The object is to provide an improved construction which shall be neat and compact, efficient in its operation, comprising a minimum of parts and adapted to be assembled with a minimum of operations.

The device comprising the invention belongs to that class of clasps having two jaw elements, and a cooperating locking member.

The distinguishing feature of the invention is that all of the elements may be completely formed before assembling, and the assembly requires the use of one pivot only, which results in a substantial saving of time and labor when the production involves a great number of said devices.

Referring to the drawing, which illustrates merely by way of example, a suitable embodiment of the invention:—

Fig. 1 is a view in perspective of the improved device secured to a supporting web.

Fig. 2 is a perspective of the device in open position.

Fig. 3 is a similar view in closed position.

Fig. 4 is a longitudinal section on line 4, 4 of Fig. 3.

Fig. 5 is a similar fragmentary view on line 5, 5 of Fig. 2.

Fig. 6 is a similar view showing the jaws only partly open.

Fig. 7 is a detail in plan.

Fig. 8 is a perspective view of the locking member.

Similar numerals refer to similar parts throughout the several views.

In the drawing above described, Fig. 1 is substantially full size. Figs. 2, 3, 7 and 8 are on an enlarged scale, while Figs. 4, 5 and 6 are on a still larger scale.

The jaw member 15 comprises a substantially flat plate with a slightly curved rear flange 16, and flanking side flanges or wings 17 and 18. These side flanges are spaced apart to provide the slots 19, and the flanges 17 have arcuate recesses 20 opening to the slots 19. The flanges 18 are provided with holes for receiving the pivot pin 21. The jaw member 22 is also a substantially flat plate of slightly lesser dimensions than the plate 15. Member 22 is provided with flanking ears 23 provided with holes for receiving the pivot pin 21. Members 15 and 22 are shown as provided with slight flanges 24 and 25 respectively which are adapted to overlap for securing a more effective grip of the garment such as 26,

with which the jaws engage. Other means may obviously be employed for this purpose, such for example as corrugating the engaging faces or faces of the jaws as providing frictional pads of rubber, felt or similar material.

A suitable spring such as 27 is provided, supported by the pivot pin 21 having extensions 28 and 29 for engaging the inner sides of the members 15 and 22 respectively.

A combined web engaging and locking member 20 is associated with the jaw members 15 and 22 to cause the closing of the jaws and to lock the same closed against the tension of spring 27 and to permit the opening of the jaws in response to the normal action of said spring.

This locking member 30 is provided with the slot formation 31 for receiving the web or band 32. The bar formation 33 is interrupted midway its extension leaving a space 34 between its two inner ends and is provided at said inner ends 70

with the arcuate wings or arms 35. At the outer ends of the arm 35 is provided an extension 36 connecting said arms 35 and extending in a plane at right angles with the slotted portion of said member 30. A substantial part of this extension 80

merges with the outer or lower ends of arms 35 as shown in Fig. 8. Beyond the ends of the arms 35 the extension 36 is narrowed between the two marginal sides 36' as shown in said figure. The margin 37 and the dotted line 37' indicate the 85

limits of the imaginary bar 38 which extends from the outer side margin of one arm 35 to the outer side margin of the other arm 35, while the balance of extension 36 extends only to the inner side margin 36' of one arm 35 to the inner 90

side margin 36' of the other arm 35, thereby providing offset portions 39 at the end of each arm 35.

In the section views, Figs. 4, 5 and 6, the imaginary bar 38 is differently shaded from the 95 extension 36, although the sections are in the same plane, merely for illustrative purposes.

In describing the recesses 20, in the flanges or wings 17, as arcuate, it is meant that said recesses 20 have arcuate margins, as at 20', in 100

said wings.

In assembling the device, the offset portions 39 or outer extensions of the imaginary bar 38 of member 30 are passed into the slots 19 of member 15, with the extension 36 projecting upwardly 105 from the inner side of member 15, the member 30 is then turned so that extension 36 will be flat upon the said inner side of member 15 with the outer end of said extension 36 in close proximity to the inner surface of the slightly curved 110

flange 16 as shown in Fig. 5. The jaw member 22 and spring 27 are then assembled with member 15 by means of the pivot pin 21 as shown in the drawing and the device is complete.

5 The operation is as follows:—

It will be noted that when the parts are assembled as above described, the margin 37 of the locking member is always held against the inner face of jaw element 15 by the force of 10 the spring actuated jaw member 22 cooperating with the curved margins 20' of wings 17. The arms 35 flank the outer side margins of the member 15, and thus prevent relative lateral movement. As the locking member 30 is moved 15 from the locking to the unlocking position, and vice versa, the margin 37 slides along the inner surface of member 15, while the offset portions 39 slide upon the arcuate or curved margins 20' of the wings or flanges 17. When the element 20 30 is brought into the position shown in Fig. 4, the extension 36 forces the member 22 into locking engagement with member 15. When element 30 is moved into the position shown in Fig. 5, the extension 36 lies flat against the underside of member 15, thus permitting member 25 22 to assume the open position. The inner surface of the curved flange 16 engaging with the adjacent end of extension 36 also cooperates in the movement of member 30 into the position 30 shown in Fig. 5.

What I claim is:—

1. A clasp comprising cooperating jaw members pivoted together, one jaw member provided on each side with flanges providing oppositely disposed slots and a locking member having portions seated in said slots and held against displacement by the combined action of said members.

2. A clasp comprising cooperating spring controlled jaw members pivoted together, one jaw member provided on each side with flanges providing oppositely disposed slots and a locking member having portions seated in said slots and held against displacement by the combined action 40 of said members.

3. A clasp comprising cooperating jaw members pivoted together, one jaw member provided on each side with flanges providing oppositely disposed slots and a locking member having arms flanking the side margins of a jaw member and having portions seated in said slots and held against displacement by the combined action of 80 said members.

4. A clasp comprising cooperating jaw members pivoted together, one jaw member provided on each side with flanges providing oppositely disposed slots with offsets having arcuate margins and a locking member having portions seated in 85 said slots and held against displacement by the combined action of said members.

5. A clasp comprising cooperating jaw members pivoted together, one jaw member provided on each side with flanges providing oppositely disposed slots with offsets having arcuate margins and a locking member having portions seated in 90 said slots and portions having movable engagement with said arcuate margins and held against displacement by the combined action of said members.

6. A clasp comprising cooperating jaw members pivoted together, one jaw member provided on each side with flanges providing oppositely disposed slots and a locking member having portions seated in said slots and held against displacement by the combined action of said members, 100 said locking member provided with a margin having sliding engagement with the inner surface of a jaw member.

7. A clasp comprising cooperating jaw members pivoted together, one jaw member provided on each side with flanges providing oppositely disposed slots and a locking member having portions seated in said slots and held against displacement by the combined action of said members, 110 said locking member provided with a margin having sliding engagement with the inner surface of a jaw member and an oppositely disposed margin adapted to engage the inner surface of the other jaw element.
